UNITED STATES PATENT OFFICE.

GEORGE WILBER THORPE, OF GENEVA, NEW YORK.

FUR-STRETCHER.

1,110,016.

Specification of Letters Patent.

Patented Sept. 8, 1914.

Application filed November 6, 1913. Serial No. 799,545.

To all whom it may concern:

Be it known that I, GEORGE WILBER THORPE, a citizen of the United States, residing at Geneva, in the county of Ontario 5 and State of New York, have invented certain new and useful Improvements in Fur-Stretchers; and I do declare the following to be a full, clear, and exact description of the invention, such as will enable 10 others skilled in the art to which it appertains to make and use the same.

This invention relates to hides, skins, and leather; and more especially to apparatus for stretching furs and pelts; and the object of the same is to produce a stretcher of this kind which can be made so cheaply 15 that the user can have them in a variety of sizes adapted to any particular pelt or fur.

A further object is to produce a stretcher 20 which is exceedingly simple and therefore not likely to get out of order, and quite cheap so that it is placed within the reach of trappers, furriers, and others who treat skins in this way.

25 These objects are carried out by constructing the stretcher in the manner described below, and shown in the drawings wherein—

Figure 1 is a perspective view of this 30 device complete, and Fig. 2 is an enlarged side elevation or edge view of the lower end thereof. Figs. 3 and 4 are sectional views on the lines 3—3 of Fig. 1 and 4—4 of Fig. 2 respectively. Fig. 5 is a perspective detail of the latch.

Considerable objection to devices of this character has arisen in the past in that they generally have prongs or spurs which puncture the hide or skin and which, being ordinarily carried by the movable member, strain open the openings or holes they make and stretch the product in strips or tongues when said member is adjusted. This objection I overcome by employing a clamp 40 which does not cut or puncture the hide at all and which grips it completely across its width so that when moved to put tension on the hide the latter is not torn or mutilated and is not stretched into tongues 45 or strips. In the embodiment of my invention shown in the drawings the fixed member is made of one piece of stiff wire. Beginning at the point 1, I first bend the wire into a hook 2 standing in a horizontal 50 plane, then laterally outward in an arm

3, then straight upward in a side bar 4 which is curved inward to form one side 5 of the head of the spring, then the wire is formed into a coil or eye 6, and carried downward on a curved line to form the 60 other side 7 of the head, thence the wire passes straight downward to form the remaining side bar 8, and is turned inward into a second horizontal arm 9 standing in alinement with the first arm 3, and the 65 inner end of this arm is formed into an ogee bend 10 which embraces the hook 2, and thence the wire is carried straight upward in a central bar 11 and engaged with the eye 6 by a hook 12. Thereby is formed a 70 frame which has three upright bars, 4, 11, and 8, all parallel with each other excepting that the upper ends of the side bars 4 and 8 are curved inward at 5 and 7 to produce a head; and as these bars throughout the 75 major portion of their length stand parallel with each other, the movable member or block may slide thereon with ease. It will not be necessary for the purposes of this specification to amplify the manner in 80 which this member or in fact any part of the device is made.

The movable member has a body-portion consisting of a block 13 preferably of wood having upright grooves 14 at its opposite 85 ends covered with plates 15 which may be screwed to the ends of the blocks as at 16 to close the grooves and thereby form guides for the side bars 4 and 8; and the block 13 also has a central guide for the intermediate bar or arm 11. In the lower edge of the block a notch 18 is formed, and pivotally mounted on a staple 19 in the block is an eye 20 at the rear end of a latch as seen in Fig. 5, and this comprises a body consisting of a flat metal plate 21 having a slot 22 of a size to loosely receive the central bar 11. An expansive spring 23 is coiled on this bar between the block and latch and throws the latter downward into biting engagement with the bar so as to resist the upward movement of the block and the entire movable member. But when the tip of the latch is raised by the thumb or finger of the operator, the movable member may 100 be adjusted up and down upon the frame in a manner which will be clear.

A clamp is provided for holding one end of the skin or hide, which latter is usually in the shape of a fur as designated by dotted 110

lines in Figs. 1 and 2, but if said skin be that of an ordinary four-legged animal its either end is passed over the head of the framework and its other end is engaged 5 with the movable member by means of the clamp, after which this member is adjusted downward along the upright bars of the frame to stretch the skin, and is held in adjusted position by means of the latch. 10 This clamp, as above suggested, does not perforate the fur or skin at all, and is intended to grip it for its full width; and by preference I make the clamp of stout wire as shown. Each side of the block 13 15 is grooved transversely as at 30, and coacting with said groove is a stretch of wire constituting a jaw 31. From each end of this stretch the wire passes outward in an arm 32 and thence downward in a second arm 33 so as to produce an L-shaped member, and the lower end of this member is turned laterally outward into a foot 34 which is pivoted in an aperture through an ear 35 at the lower end of one of the plates 15. At 20 one side of the stretcher, the foot is then bent upward into an arm 36, and the corresponding foot of the other clamping member is bent up into a similar arm 37 which at its upper end is carried inward into a hook 38 adapted to engage the first arm 3 25 when the gripping jaws 31 are pressed closely into the two grooves 30. Thus it will be seen that the clamping members are virtually hinged to the lower edges of the block 13, and their arms 36 and 37 are latched together when their jaws are at 30 work; while the block is latched to the central bar 11 of the main frame so as to hold it at the proper distance below the head of 35 such frame to stretch the fur or pelt F. The operation of the device will be well understood by those familiar with this art.

What is claimed as new is:

1. A fur stretcher comprising a skeleton 45 frame having a head at one extremity for engaging one end of the fur, a movable member consisting of a block slidably mounted on said frame and having grooves across both side faces, clamps hingedly connected with the lower corners of the block 50 and having jaws registering with said grooves, and means for holding the jaws in the grooves, for the purpose set forth.

2. A fur stretcher comprising a skeleton 55 frame having a head at one extremity for engaging one end of the fur, a movable member consisting of a block slidably mounted on said frame and having grooves across both side faces, plates secured to the 60 ends of said block and having perforated ears projecting beyond its side faces at its lower corners, clamping jaws having feet pivotally mounted in the perforations of said ears, said jaws having gripping portions 65 registering with said grooves, and

means for rocking the clamps on their pivots to throw the gripping portions of the jaws into such grooves.

3. A fur stretcher comprising a skeleton frame having a head at one extremity for engaging one end of the fur, a movable member consisting of a block slidably mounted on said frame and having grooves across both side faces, plates secured to the ends of said block and having perforated 75 ears projecting beyond its side faces at its lower corners; on one side of the block a clamping member of stiff wire having a jaw co-acting with said groove, arms at its ends having feet with their lower extremities pivoted in the perforations of said ears, and one of the feet carried thence upward in an arm; and at the other side of said block a similar clamp whose upwardly extending arm has an inturned hook adapted to engage the arm of the first-named clamp, for the purpose set forth.

4. A fur stretcher consisting of a frame member made of stiff wire comprising three substantially parallel bars connected by cross arms at their lower ends and the side bars bent inward at their upper ends into a head and united by an integral eye with which the upper end of the intermediate bar connects; and a movable member slidably mounted on said frame, a latch for holding it in adjusted position, and clamps on its side faces for engaging the fur.

5. A fur stretcher consisting of a frame member made of stiff wire comprising three substantially parallel bars connected by cross arms at their lower ends and the side bars bent inward at their upper ends into a head and united by an integral eye with which the upper end of the intermediate bar connects; and a movable member having guides engaging said bars and consisting of a block notched in its lower edge around the intermediate guide, a latch disposed within said notch and pivotally connected at 100 one end with the block, its body having a slot loosely engaging said intermediate bar, a spring between the latch and block and throwing said slot into biting engagement with said bar, and clamps mounted on opposite faces of the block for grasping the fur.

6. A fur stretcher consisting of a frame member made of stiff wire comprising three substantially parallel bars connected by cross arms at their lower ends and the side 110 bars bent inward at their upper ends into a head united by an integral eye with which the upper end of the intermediate bar connects; and a movable member consisting of a block having upright grooves in each end 115 and an upright hole through its center, all forming guides for the bars of said frame, plates secured over said grooves and having bearings, clamps pivotally mounted in said 120 bearings and having jaws, means for hold- 125

ing said jaws in forcible contact with the sides of the block for gripping the fur, and a latch carried by the lower edge of the block for holding the same in adjusted position 5 on the intermediate bar of the frame.

7. In a fur stretcher, the combination with a movable member having three parallel guides, and fur-gripping devices carried by this member; of a frame member made of 10 stiff wire bent as follows, to wit: starting with a hook standing in a horizontal plane, thence extending horizontally in an arm, thence carried vertically upward in a straight side bar and bent inward, thence 15 formed into a central eye, then bent outward and downward and carried thence straight

downward into an opposite side bar, thence carried straight inward in a second arm in alinement with the first, thence formed into an ogee curve engaging said hook, thence 20 carried straight upward in an intermediate bar parallel with the two side bars, and finally formed into a hook engaging said eye.

In testimony whereof I have hereunto set 25 my hand in presence of two subscribing witnesses.

GEORGE WILBER THORPE.
